CLAIM

The ornamental design for a multi-sided cutting instrument for mobilizing small bones in the foot as shown and described.

DESCRIPTION

FIG. 1 is a perspective view of our new design for a multi-sided cutting instrument for mobilizing small bones in the foot according to a first embodiment;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a perspective view of our new design for a multi-sided cutting instrument for mobilizing small bones in the foot according to a second embodiment;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The dashed broken lines illustrate portions of the multi-sided cutting instrument for mobilizing small bones in the foot that form no part of the claimed design.

The dot-dash broken lines illustrate boundaries of the multi-sided cutting instrument for mobilizing small bones in the foot that also form no part of the claimed design.
